PHOTOGRAPHIC MATERIAL FOR THE MANUFACTURE OF COLOR IMAGES

Louis Achilles Meeusen and Albert Bellay, Mortsel-Antwerp, Belgium, assignors to Gevaert Photo-Producten N. V., Mortsel-Antwerp, Belgium, a company of Belgium

Application August 8, 1947, Serial No. 767,586
In Germany December 3, 1942

Section 1, Public Law 690, August 8, 1946
Patent expires December 3, 1962

1 Claim. (Cl. 95-2)

This invention relates to the production of color images by means of diffused silver halide. It is an improvement of the process disclosed in Patent 2,352,015, according to which photographic reversal images are obtained when the silver halide which was not affected by light during an exposure of a silver halide layer, is caused to diffuse into, and to be reduced in a receiving layer, which is not sensitive to light. In applying this principle, the sensitive layer and the receiving layer may be coated onto two separate supports. After exposure, the sensitive layer is pressed upon the receiving layer in the presence of substances, necessary for producing the positive reversal image, either by direct reaction with the diffused silver halide or by induced reaction or by catalytic reaction.

Instead of using separate supports for the sensitive layer and for the receiving layer, both these layers may be coated on one support. Substances which speed up the reduction of silver halide not affected by the light in the presence of a silver halide solvent i. e. reduction and crystallisation nuclei for silver halide, and substances capable of forming such nuclei by reaction with silver halide, may be mixed in the sensitive layer. In either case, besides silver images, also color images are obtainable directly, for instance, a receiving layer containing an adequate dyestuff for the silver bleaching-out process may be used. This dyestuff is bleached out in proportion to the silver of the reversal image in the receiving layer and in this way a color image is produced.

The reversal image may also be formed by color development. One method consists in developing the exposed material in a usual developer, allowing the not-reduced silver to diffuse into and to be reduced in the receiving layer, re-halogenizing the secondary image and finally re-developing the halide thus formed in a color developer. After removing the two silver images, a colored secondary image is left.

The diffusion and the color-image formation can also be carried out in a single treatment. To this end, the material is washed after the first development as usual in order to altogether remove the developer. It is then treated in a color developer containing a silver salt solvent. The not-reduced silver salt diffuses into the receiving layer forming therein both a silver image and a color image by the action of the substances accelerating the reduction. To those skilled in the art of color photography, it is obvious that the color couplers may be present in the color developer or in the receiving layer.

In case the coupler in the receiving layer is diffusion-fast, the silver salt solvent may be added to the primary developer. The diffusion of the not-reduced silver halide consequently already takes place after the first development in such a way that a primary negative image is formed in the emulsion layer and at the same time a secondary positive image in the receiving layer. After washing, the two silver halide images are re-halogenized and re-developed in a color developer; now a negative silver image is formed in the emulsion layer and a color image simultaneously with a positive silver image in the receiving layer.

It is to be noted that this process only yields single-color images.

It is an object of the present invention to provide new photographic processes for the manufacture of color images by diffusion and reduction in the presence of a silver halide solvent of the silver halide, not affected by light, of the light-sensitive layer in a not-sensitive receiving layer containing substances which accelerate the reduction of silver halide not affected by light such as reduction and crystallisation nuclei for silver halide substances capable of producing such nuclei by reaction with silver halide.

It is another object of the present invention to provide a new photographic material adapted for use in the above process.

Further objects will appear from the following description.

In order to obtain multi-color reproduction, at least two single-colored part-images are required, which means that for color photography according to our present process, a material theoretically should consist of at least two, preferably three emulsion layers and also of their respective receiving layers. Since one of the emulsion layers necessarily is in contact with two receiving layers, the not-reduced silver salts of this emulsion can diffuse into two different receiving layers i. e. two different colored positive images may correspond to one part-image which results in an incorrect colour rendering. It was found that by providing a barrier layer all undesired diffusion from an emulsion layer into a receiving layer may be avoided.

A photographic multi-layer according to our invention which allows obtaining multi-color images according to the diffusion principle in a simple and positive way, contains the usual sensitive layers, corresponding receiving layers and at least one barrier layer which forms the separation between a sensitive layer and an adja-

cent receiving layer. These barrier layers are characterized thereby that they contain substances which check the diffusion of the silver salts either by catalytic action or by chemical reaction. Such substances are development nuclei, such as colloidal silver, silver sulphide, fogged silver halide emulsion and others, as described in Patent 2,352,014. The diffused salt probably will be decomposed, by the catalytic action of the development nuclei, to metallic silver which is precipitated in the barrier layer and subsequently is removed simultaneously with the silver image.

The barrier action may be obtained also by using substances which precipitate the diffusing complex silver salts, such as for instance the known photographic stabilizers having a reactive hydrogen atom in an amino- or a mercapto group.

The thickness of a barrier layer required, depends upon different factors such as e. g. the nature and the concentration of the development nuclei and precipitating substances, the concentration of complex silver salts, the nature of the developers used whilst reducing the diffusing silver salt etc.

As set out before, the barrier layer is arranged between an emulsion layer and a receiving layer. This arrangement, however, can be varied within wide limits. A receiving layer e. g. may be functioning as barrier layer which is of primary importance for a material wherein the two receiving layers of two succeeding sensitive layers are coated in superposition in between the said sensitive layers. In this case, the barrier action of the receiving layers may be increased by correspondingly varying the thickness of the layers or by a greater concentration of development nuclei and precipitating substances. Sometimes, it may be useful to arrange an extremely thin barrier layer between the two receiving layers.

Of particular value is a layer containing both the sensitive salts and the receiving substances according to applicants' French Patent 53,513. When three such layers are used, it may suffice to apply two barrier layers between the three layers. The process can be simplified further by an addition of the dye-stuffs of the filter layers or of the anti-halation layers in one or more layers at will.

Treatment of photographic material according to this invention is simple and can be carried out by any person slightly skilled in the art of photography. For instance, when color development is used, the three primary part images are developed in a usual photographic developer. Next the remaining developer is completely removed by thorough washing. The material is further treated in a color developer containing a solvent for silver salts as fully described in Patent Number 2,352,014.

In this developer, the remaining silver salts diffuse from every emulsion layer into the corresponding receiving layer and are reduced upon the development nuclei; simultaneously the oxidation products of the developing agent are coupled with the diffusion-fast color coupler, which is contained in every receiving layer. In this way, dyestuffs are obtained which correspond to the optical sensitization of each sensitive emulsion layer. After removing the metallic silver, the color image appears.

In the process according to the silver bleach-

ing-out method the material is treated correspondingly.

The invention, as a matter of fact, is not limited to the use of the silver bleaching-out method 5 nor to the process of the color development. All other processes, however, applied in color photographic technics may be used separately as well as simultaneously and at will. In this connection, a three-layer material may be used where- 10 in the receiving layer of the blue-sensitive layer contains a yellow dyestuff, which afterwards is destroyed according to the silver bleaching-out process, whilst both the other receiving layers contain diffusion-fast color couplers which by 15 color development produce a color image.

The color images obtained by color development are distinguished by a particular purity of colors. The reduction of the diffusing silver salt forms metallic silver in an extraordinarily finely- 20 divided state, so that the dyestuff obtained produces a favourable absorption curve.

The new material can be used for the production of either negative images or positive images, transparent images as well as of images to be 25 viewed by reflected light.

Being included in the receiving layers, the different diffusion-fast dyestuffs or color couplers are separated from the sensitive emulsion so that any undesired influence of these sub- 30 stances upon the photographic emulsion is prevented.

This invention will further be described in detail, and by way of examples, with reference to the accompanying drawing wherein Figs. 1, 35 2 and 3 are diagrammatic sections of different photographic materials employed in accordance with the invention as described in the following examples.

Example 1

40 A material is used according to Fig. 1, wherein the following layers are arranged on the support:

- (1) A receiving layer with development nuclei (for instance colloidal silver) and a diffusion-fast blue-green color coupler.
- (2) A red-sensitive silver halide emulsion layer,
- (3) A barrier-layer with development nuclei,
- (4) A green-sensitive silver halide layer,
- (5) A receiving layer with development nuclei and a diffusion-fast magenta color coupler,
- (6) A receiving layer with development nuclei (yellow colloidal silver) and a yellow diffusion-fast color coupler,
- (7) A blue-sensitive silver halide layer.

55 After exposure, this material is developed in the following bath (1):

Metol	-----	g--	1
Sodium sulphite (cryst.)	-----	g--	10
Hydroquinone	-----	g--	3
Sodium carbonate (cryst.)	-----	g--	100
Potassium bromide	-----	g--	2
Water	-----	ccs--	1000

60 It is then washed and treated in the following bath (2):

Sodium sulphite (cryst.)	-----	g--	5
N,N-diethyl-p-phenylene diamine hydrochloride	-----	g--	4
Sodium thiosulphate (cryst.)	-----	g--	3
Sodium carbonate (cryst.)	-----	g--	80
Water	-----	ccs--	1000

70 Both a silver image and a color image are formed upon the development nuclei in the lay-

ers 4, 5 and 6, which images are positive in respect to the adjacent emulsion layer. It was not necessary to provide a barrier layer between the receiving layers 5 and 6, the concentration of the development nuclei being sufficiently high. In this case, the diffusing silver salts from the layers 4 and 7 are wholly reduced. Consequently, no diffusion from the layer 4 into the layer 6 or from the layer 7 into the layer 5 takes place.

After washing and removing both the remaining silver salt and the silver image formed, a pure color image is obtained.

Example 2

A material according to Fig. 2 containing the following layers upon the support is used:

- (1) A red sensitive silver halide emulsion wherein hardened gelatine grains are dispersed which contain development nuclei and a diffusion-fast blue-green color coupler,
- (2) A barrier layer containing a fine silver chloride emulsion fogged by exposure,
- (3) A green-sensitive silver halide emulsion wherein hardened gelatine grains are dispersed containing both development nuclei and a diffusion-fast magenta color coupler,
- (4) A barrier layer containing colloidal silver as development nuclei,
- (5) A blue-sensitive silver halide emulsion wherein hardened gelatine grains containing both development nuclei and a diffusion-fast yellow color coupler, are dispersed.

This material, after exposure, is developed in the first bath of Example 1, washed and color-developed in bath 2 until the color images formed in the grains are of sufficient intensity. The remaining silver salts and the silver formed, are removed after washing in the known manner.

Example 3

The material is the one described in Example 2. The diffusion is not induced while developing in bath 2, but during the first development by adding 2 g./liter of sodium thiosulphate to the bath 1. Whilst developing in this developer the negative silver images are formed in the layers and positive silver images in the grains. After fixing and washing, the silver of the image is re-halogenized in the following bath:

Potassium ferricyanide-----	g--	25
Potassium bromide-----	g--	10
Water -----	ccs--	100

The image is washed and re-developed in a developer which contains a known cyclic diamine as reducer. During this development silver images are formed in the emulsion layers and both silver images and positive color images in the grains which contain the color components. After washing and removing the silver, a color image is left.

Example 4

A material is used according to Fig. 3 containing the following layers upon the support:

- (1) A layer which contains development nuclei and a diffusion-fast blue-green azodyestuff,
- (2) A red-sensitive silver halide emulsion,
- (3) A barrier layer containing a binding agent and development nuclei,
- (4) A layer, containing a binding agent, development nuclei and a magenta dyestuff,
- (5) A green-sensitive silver halide emulsion,
- (6) A barrier layer as described above,

- (7) A layer, containing a binding agent, development nuclei and a diffusion-fast yellow azodyestuff,
- (8) A blue-sensitive silver halide emulsion.

After exposure, this material is treated in the following bath:

Metol -----	g--	2
Sodium sulphite (cryst.)-----	g--	50
Hydroquinone -----	g--	6
Sodium carbonate (cryst.)-----	g--	100
Potassium bromide-----	g--	2
Sodium thiosulphate-----	g--	2.5
Water -----	ccs--	100

Negative silver images are formed in the emulsion layers and positive images in the layers 1, 4 and 7. After fixing and washing, the material is treated in a bleaching bath whereby the azodyestuffs in the layers 1, 4 and 7 are bleached-out according to the silver bleaching-out process. The silver is then rehalogenized and removed by fixation.

Various changes may be made in the process and materials described above without departing from the principle on which the invention is based.

We claim:

A photographic material comprising in superposition:

1. A support;
2. A layer containing a diffusion-fast blue-green color former capable of coupling with the oxidation products of a primary aromatic amino developer to form a dye image and a substance selected from the group consisting of heavy metals, insoluble sulfides of such metals and fogged silver halide emulsion;
3. A red-sensitive silver halide emulsion layer;
4. A barrier layer containing a substance selected from the group consisting of heavy metals, insoluble sulfides of such metals and fogged silver halide emulsions;
5. A green-sensitive silver halide emulsion layer;
6. A layer containing a yellow diffusion-fast color former capable of coupling with the oxidation products of a primary aromatic amino developer to form a dye image and a substance selected from the group consisting of heavy metals, insoluble sulfides of such metals and fogged silver halide emulsion;
7. A blue-sensitive silver halide emulsion layer.

LOUIS ACHILLES MEEUSSEN.
